UNITED STATES PATENT OFFICE

162,486

ROOM SERVICE UTILITY CART
OR THE LIKE

Otto L. Snapp and Otis L. High, Columbus, Ohio, assignors to White Castle System, Inc., Columbus, Ohio, a corporation of Delaware

Application August 30, 1950, Serial No. 11,994

Term of patent 14 years

(Cl. D14—3)

To all whom it may concern:

Be it known that we, Otto L. Snapp and Otis L. High, each a citizen of the United States, residing at Columbus, in the county of Franklin and State of Ohio, have invented a new, original, and ornamental Design for a Room Service Utility Cart or the like, of which the following is a specification, reference being had to the accompanying drawing, forming a part thereof.

Fig. 1 is a perspective view of a room service utility cart, showing our new design;

Fig. 2 is a top plan view thereof;

Fig. 3 is an end elevational view;

Fig. 4 is a side elevational view.

We claim:

The ornamental design for a room service utility cart or the like, substantially as shown.
OTTO L. SNAPP.
OTIS L. HIGH.
